UNITED STATES PATENT OFFICE.

FRANK H. BALL, OF DETROIT, MICHIGAN, ASSIGNEE, BY MESNE ASSIGNMENTS, TO
BALL AND BALL CARBURETOR COMPANY, OF DETROIT, MICHIGAN, A PARTNER-
SHIP COMPOSED OF FREDERICK O. BALL AND CORNELIA M. BALL.

CARBURETOR.

Application filed March 7, 1918. Serial No. 220,863.

To all whom it may concern:

Be it known that I, FRANK H. BALL, a citizen of the United States, residing at Detroit, in the county of Wayne and State of Michigan, have invented new and useful Improvements in Carburetors, of which the following is a specification.

This invention relates to carburetors and consists in certain improvements in the construction thereof as will be hereinafter fully described and pointed out in the claims.

The carburetor comprises a primary carburetor adapted to utilize a higher volatile fuel, such as gasoline and a secondary carburetor adapted to use a less volatile fuel such as kerosene. While the primary and secondary carburetors have advantages independent of their association with each other, they are, however, particularly advantageous in their construction in such relation.

The combined device is designed to utilize gasoline in the primary carburetor for starting and slow running when the air velocities are insufficient to thoroughly atomize kerosene so as to make it readily available, also when the exhaust heat is insufficient to vaporize kerosene. The primary carburetor is designed to deliver the fuel in the form of an emulsion to the point of greatest air velocity in said primary carburetor and is so designed as to deliver a properly proportioned mixture of air and vapor throughout the range of the carburetor while acting independently as a primary carburetor without the use of yielding valves.

The secondary carburetor which is designed to use kerosene is arranged to automatically come into operation when the requirements are such as to give an air velocity which will sufficiently atomize kerosene to assure its ready combustion. In this connection it is desirable to offer as little resistance to the flow of air as possible and consequently having provided means acting only when conditions are such as to produce permissible air velocity in the secondary carburetor, the apparatus is so designed that this initial velocity is not much exceeded in the more restricted portions of said carburetor as the demands for air through it increase. In this way the resistance to the flow of air is at no time excessive.

The invention is illustrated in the accompanying drawings as follows:

Fig. 1 is a section on the lines 1—1, 7—7, 1^a—1^a and 1^b—1^b in Fig. 4.

Fig. 2 is a section on the line 2—2 in Fig. 1.

Fig. 3 is a side elevation of a part of the carburetor showing the lever for holding the yielding valve of the secondary carburetor closed.

Fig. 4 is a section on the lines 4—4 in Figs. 1 and 2.

Fig. 5 is a detail view in section on the line 5—5 in Fig. 4.

Fig. 6 is a detail view in section on the line 6—6 in Fig. 4.

Fig. 7 is a detail view in section on the line 7—7 in Fig. 4.

Fig. 8 is a detail view in section on the line 8—8 in Fig. 2.

1 marks the carburetor body, 2 the gasoline receptacle, or float chamber, 3 the kerosene receptacle or float chamber, 4 the main mixing chamber, or the combined suction passage, 5 an upper flange to adapt it to be readily secured to a manifold or other passage leading to an engine, 6 a throttle valve, 7 a rock shaft carrying the throttle valve 6, and 8 the usual lever for operating the throttle valve.

The suction passage of the primary carburetor is provided with a restriction in the form of a Venturi tube 9. This tube has a screw-threaded end 10 which is screwed into a screw-threaded opening 11 in the walls of the passage. The Venturi tube has a shoulder 12 at its bottom which engages an annular shoulder 13 in the suction passage. An annular enlargement 15 is formed in the passage between the shoulder 13 and the screw threads 11 and 95 the Venturi tube forms a closure at the top and bottom of this enlargement forming a chamber or well 16. An air opening 17 leads from the inlet passage 14 below the Venturi tube to this well and spray nozzles 18 extend from the well into the Venturi tube, the outlets of the nozzles extending inwardly from the wall of the Venturi tube just above its greatest restriction, the spray nozzles being inclined and the bottoms of the spray nozzles extending to a point in the well below the gasoline fuel level G—G as established by the float chamber.

Fuel is delivered to the well 16 from the float chamber 2. This float chamber is of the usual form having the inlet 19, valve 20 controlling the inlet, stem 20^a extending 5 from the valve, collar 21 on the stem, levers 22 engaging the collar and the float 23 operating on the levers in the usual manner to control the valve 20 and thus control the fuel level in the receptacle. The fuel flows 10 from the receptacle to an outlet passage 24 which terminates in an extension 25. A hollow screw 26 extends through this extension and into a passage 27 formed in the carburetor body 1. An opening 28 forms 15 a connection between the opening 29 within the screw and the passage 24. A screw plug 30 is screwed into the upper end of the passage 27. This plug extends into the end of the screw 26. The screw plug 30 has a 20 passage 31 within it and the plug extends into the passage 29 so that the opening 31 in the passage 29 makes a continuous passage. A calibrated plug 32 is screwed into the end of the passage 31. Radial openings 33 extend through the wall of the plug 30 forming a means of communication between the passage 31 and the passage 27 outside of the screw plug. An opening 34 extends from the passage 27 into the well 16 25 and delivers fuel to the well 16. It will be noted that the radial openings 33 and the opening 34 are below the fuel level so that fuel is delivered to the well 16 by gravity.

35 The choke valve 35 is provided at the inlet to the suction passage of the primary carburetor. This is carried by the rock shaft 36 and can be operated by a lever 36^a. It is desirable to provide means for sup- 40 plying the engine during idling with a very uniform mixture of highly atomized fuel. This is preferably done by delivering fuel above the throttle and this is accomplished in this carburetor by taking fuel and air 45 from the connection 34 leading to the well 16. A passage 37 is arranged in the body of the carburetor and connects with the well 34 (see Fig. 5). A vertical passage 38 extends from the passage 37 and is connected 50 by a tube 39 with a passage 41 in a projection 40 on the wall of the carburetor body. A nozzle 42 extends from the passage 41 into the suction passage just above the throttle. The passage 41 is plugged by a 55 screw 43. When the throttle is closed fuel and air are drawn up through the passages just enumerated and delivered above the throttle. This is sufficient to maintain the engine while idling in a well known manner. Air is supplied in this operation by 60 way of the well and passage 34.

In the operation of the primary carburetor it will be understood that initially there is a level of fuel in the well as controlled by 65 the float chamber on the line G—G. In the ordinary operation of carburetors, the first flow will be through the idling tube which has a very strong suction and almost immediately creates a spray condition and reduces the level in the well so that as the throttle is opened, the spray is carried initially through the nozzles. If, however, the throttle is so suddenly opened that this preliminary movement through the idling tube does not take place, then there is an initial movement of solid liquid through the nozzles immediately followed by the spray. Air passes through the openings 17 to the well and fuel passes through the openings from the fuel receptacle by way 75 of the passages 24, 28, 32, 31, 33 and 34 to the well. It is well understood that one of the primary but most difficult problems in carburetor construction is the maintenance of a desired relation between the air 80 and fuel delivered to the carburetor. The high velocity through the Venturi tube reduces the pressure in this tube considerably below the pressure above the Venturi tube. This reduced pressure induces a very high 85 velocity in the spray nozzles so that the fuel is atomized. This movement of air through the spray nozzles toward the lower pressure in the Venturi tube reduces the pressure in the well slightly below atmospheric 90 pressure so that the pressure in the well is intermediate. While the opening 17 is shown comparatively large and is in effect directly open to the atmosphere so that the 95 reduction in pressure in the well is comparatively slight it will be readily understood that a variation in this opening will vary the reduction in the well and consequently the fuel flow due to this action. 100

It will further be understood that this atmospheric supply of air through the opening gives a constant and thus reduces the variables which are encountered in maintaining the proportions of fuel and air. This in turn induces a flow of air through 105 the opening 17 and also induces a flow of fuel through the opening 34 to the well. Inasmuch as the velocity of the air through the well sweeps the fuel from this well in the form of a spray through the nozzles 110 a negative head is avoided in the elevation of this fuel from the fuel level of the float chamber to the upper end of the nozzle because when the fuel is sprayed in the form 115 of an emulsion it ceases to have an undesirable gravity effect.

In many carburetors, in fact, the greater number of them, fuel has been delivered in liquid state from a nozzle into the air current and in order to prevent the overflow from this nozzle when the carburetor is not in use it has been necessary to make the delivery end of this nozzle above the fuel level. This has created what is usually 120 termed a "negative head" and it has been 125

130

necessary to have a certain amount of suction in order to bring the gasoline up to the discharge point and this suction involves the passage of air through the carburetor. In consequence the flow of air and flow of gasoline has not been coincident and the proportioning, therefore, of the gasoline and air cannot be attained without some means of correcting the difference in the initial feeding action of the two elements. With the device here shown, it will be noted that the upper ends of the spray nozzles are above the fuel level so as to prevent the leakage from the carburetor when not in use. At the same time the air sweeps up the fuel in the form of a spray and carries it through these spray nozzles so that after the carburetor starts functioning normally there is no liquid head of fuel in these spray nozzles and in consequence no negative head to overcome so far as the fuel is concerned, the fuel flowing to the well initially by gravity and continuing its flow as induced by the reduced pressure in the well augmented slightly by gravity. Consequently the flow of air gasoline can be made approximately coincident so far as the law governing their flow is concerned and the proportioning of air and fuel can then be accomplished very nearly. It has been heretofore accomplished by a structure very similar to the one herein shown and illustrated in an application of Frederick O. Ball, dated the 28th day of December, 1916, Serial Number 139,391, in which there is a connection between the well and the mixing chamber at the discharge side of the Venturi tube, thus utilizing the lower pressure in the Venturi tube over that of the mixing chamber above it in creating a circulation carrying mixture from the mixing chamber as a spraying agent back to the well and through the spray nozzles. The connection in said structure between the mixing chamber and the well is large enough so that the dominant factor of control in the flow of fuel to the well is the pressure of the mixing chamber and fuel is fed to the well through the suction varying as the mixing chamber pressure varies. In order to obviate a tendency of the gasoline to follow along the wall of the Venturi tube it has been necessary, in the structure just referred to, to carry the spray nozzles inwardly slightly from the wall of the Venturi tube and this forms an obstruction in the Venturi tube interfering with the law governing the ordinary flow of air through a Venturi tube and consequently there is a tendency for the device to deliver a smaller quantity of air than should be delivered with the higher suction, the consequence being too rich a mixture and this corrected in the structure referred to by directing air through an automatically actuated valve at the highest velocities of the carburetor.

Where air is admitted as in the structure in this application directly to the well 16 from the atmosphere, this being the case 70 when the choke valve is open, the pressure in the well is somewhere between atmospheric pressure and the pressure in the Venturi tube as communicated to the well through the spray nozzles. With the proportion of parts shown in the drawings the reduction of pressure below atmosphere is slight but nevertheless responsive to Venturi changes. The variation of pressure in the Venturi tube unobstructed is not such as to 75 create a delivery of fuel to the well following the delivery of air through the Venturi tube, in other words, there is a variation in pressure in the Venturi tube as compared with the volume of air passing through it 80 which communicated to the well will deliver to the well fuel which will not follow proportionately the flow of air through the Venturi tube. In this case the flow of air with the Venturi tube unobstructed becomes 85 greater in proportion to the fuel fed as the velocity increases, the result being that the mixture at the higher velocities is too lean. In this construction, as in the construction which has been above referred to, in order 90 to prevent the following of the gasoline along the wall of the Venturi tube with a consequent failure of delivery to the main current, it is desirable to carry the spray nozzles into the air current passing through 95 the Venturi tube and this obstruction operates to disturb the law governing the flow of air through a Venturi tube in this structure just as in the structure above referred to but in this case this obstruction works in 100 harmony with the variation in the feeding effect of fuel to a well subjected to the varying pressures of an unobstructed Venturi tube and the feeding of air through that tube, that is to say, without such obstructions the structure here shown would produce 105 too lean a mixture at the higher velocities but these obstructions formed by the spray nozzles so disturb the action of the Venturi tube as to offset the above-described 110 tendency to produce too lean a mixture. It will be understood that the sub-atmospheric pressure in the well with the openings as indicated in the drawings in this application is slight thus requiring a comparatively 115 large fuel passage from the float chamber to the well, and it will be further understood that the degree of sub-atmospheric pressure in the well can be controlled by the size of the openings 17 and the sub-atmospheric condition being very much more pronounced with the smaller opening. The variation to the Venturi effect can be made more pronounced by increasing the obstruction provided in this instance by the nozzles. It will 120 125 130

be observed, therefore, that in this construction fuel and air can be delivered in exactly the proportions desired throughout the range of the carburetor and through fixed orifices.

5 Further that this is accomplished while delivering the fuel to the main air current fully atomized by being subjected to air at very high velocity in the spray nozzles.

The choke valve is used in this construction as it is ordinarily used to enrich the mixture, that is, to get a greater amount of suction with a less amount of air. It is desirable in order to maintain the proper proportions that the flow of air to the well 15 should also be restricted to the same extent that the flow of air to the Venturi tube is restricted and for this reason the opening 17 instead of being made to the atmosphere direct is made to the inlet of the suction tube 20 so as to be subject to the action of the choke valve. It will, of course, be understood that in the normal operation of the carburetor when running full and the choke valve is in its normal position, that is to say, wide open, 25 the opening 17 is practically the same as though it led to the atmosphere.

The carburetor so far as described may be, up to its capacity, used alone to advantage but it is particularly desirable in connection 30 with a secondary carburetor which is designed to use a less volatile fuel, such as kerosene. The successful burning of kerosene depends on complete atomization. This is accomplished in this carburetor mechanically by subjecting it to air at high velocity. It is desirable, however, to prevent the feeding of kerosene before there is a sufficient movement of air through the carburetor to supply a velocity which will accomplish this 40 purpose.

The secondary carburetor is formed in the body 1, a passage 44 being arranged in the body having an axis parallel to the axis of the passage containing the Venturi tube in 45 the primary carburetor. A shoulder 45 is arranged in this passage and a valve mounting 46 is fitted into the passage and secured by screws 47 extending into the bottom of the body. A valve 48 is carried by the valve 50 mounting and operates on a seat 49 at the upper end of this mounting. The valve is carried by a stem 50 which terminates in a head 51 and a spring 52 tensioned between the head 51 and a part of the mounting so 55 as to load the valve and hold it to its seat with a pre-determined pressure. A dash pot plunger 53 is carried by the head 51 and is provided with the usual minute opening 54. The plunger operates in the chamber 55 carried at the bottom of the valve mounting and the chamber is closed by a cap 56. The dash pot operates to prevent violent pulsations of the valve in the usual manner. The opening to the passage to the valve is 60 restricted by a perforated plate 57 at the

bottom of the passage, the perforations in this plate being so graduated as to operate with relation to the valve in a manner hereinafter described. The valve mounting has an outer ring 44 and a stem carrying 70 portion at the center supported by a spider 58, thus permitting a free passage of air through the mounting to the valve.

The kerosene receptacle, or float chamber 3 is of the usual construction having the 75 inlet 59, controlling valve 60, stem 61 extending from the valve, collar 62, levers 63 operating on the collar and a float 64 operating on the levers to control the level of fuel in the receptacle, the kerosene level being maintained at the line K-K. Fuel passes from the fuel receptacle through the extension 65 to a hollow screw plug 66 by way of the opening 66. The screw plug passes through the extension 65 and into an 80 opening 67 in the wall of the carburetor, the screw plug not only forming the connecting passage but also a means of securing the receptacle to the body of the carburetor. A screw plug 68 is screwed into the top of the opening 67 and extends down into the opening in the screw plug 66. The screw plug 68 has an opening 68. A calibrated plug 69 is arranged in the end of the plug 68 and radial passages 70 connect the opening in the screw plug with an annular chamber 71 formed in the passage 67 around the screw plug. The chamber 71 is connected by means of a passage 72 with a well 73 formed between the walls of the valve mounting 46 and the passage 44. Spray passages 74 extend from the well 73 and below the kerosene level K through the valve seat 49. These passages are arranged along the sides of the valve seat adjacent 100 to the primary carburetor so that the kerosene may be carried into and more thoroughly atomized with the gasoline from the primary carburetor. Small grooves 75 are cut into the face of the valve seat, extending to the edge of the valve seat below the point where the passages 74 open through the valve seat. The well 73 is connected by a number of air passages 76 with the suction passage between the restriction formed by the perforated plate 57 and the valve 48.

The operation of this secondary kerosene carburetor is as follows: The valve 48 is so weighted by the spring 52 that it will not open by reason of the reduced pressure in the chamber 4 until there is a sufficient reduction of pressure to create a velocity high enough through the restriction formed by the valve in its initial opening to thoroughly atomize kerosene. With the initial opening of this valve the greatest restriction is directly at the valve opening but the openings in the plate 57 also form a restriction so that the air between the valve and the plate 57 is slightly below atmospheric 110

pressure. The plate 57 forms a fixed orifice for the air and exactly the same pressure that is maintained above the plate 57 is communicated through the openings 76 to the well and induces a flow of fuel. The openings 76 are so large as compared with the passages 74 that the pressure in the well is dominated by the pressure in the chamber between the valve and the plate 57. Consequently the pressure controlling the delivery of air and fuel is substantially the same. It will be observed that there is no negative head here after the initial discharge of fuel because the well 73 is below the fuel level and the fuel is swept up and carried through the passages 74 in the form of a spray. While the passages 74 prevent the overflow they do not present a means of confining the fuel so as to make a continuous column of fuel and consequently a negative head. The fuel and air being subjected to the same inducing pressure there is a corresponding flow of fuel and air to the carburetor. As the suction increases and the requirements for a greater amount of mixture are increased the valve 48 opens and there is a greater flow of air past the valve but by reason of the restriction in the plate 57 there is not only a reduction of pressure above the valve but a reduction of pressure below the valve and the velocity of air past the valve remains for this reason more nearly constant. Consequently there is the atomizing effect which is necessary to the successful use of kerosene without undue resistance to the flow of air.

In the carburetor of the proportions here shown when running at full capacity 20% of gasoline and 80% of kerosene is utilized. This, of course, can be varied somewhat to suit the nature of running but it will be observed that in all slow running where there is the greatest difficulty in controlling the motor, the motor is operating entirely on gasoline and this is true whether the throttle is entirely open or partially closed, that is to say, the position of the throttle does not in itself control the time when the secondary carburetor begins to operate because under some conditions a wide open throttle would be accompanied with so slow a flow of air as to prevent proper atomization of kerosene and under these conditions no kerosene will be delivered. The primary carburetor under such conditions has ample capacity for the purpose.

In starting the engine, or under certain conditions, it may be desirable to cut out the secondary carburetor even when there is a high velocity of air. This may occur with a very low temperature of engine and fuel. I have provided for this by providing means whereby the valve 48 may be held in closed position. A pin 77 extends through the wall of the body of the carburetor and rests

on the valve 48. A lever 78 is pivotally mounted by a stud 79 secured to the wall of the carburetor. The lever 78 has an arm 80 contacting the push pin 77. The lever 78 may be operated in any convenient manner 70 from the dash, or otherwise to manually force the closing of the valve 48 so as to throw out of action the valve 48.

In order to supply liquid for the dash pot a passage 58^a is arranged in one of the 75 arms of the spider 58 carrying the liquid from the well to the chamber 55.

The utilization of a primary carburetor of the type here shown with a secondary carburetor permits of a very compact construction because the absence of usual parts permits of the convenient assembling of the receptacles with the body of the carburetor and the suction passages of the primary and secondary carburetors with relation to each 80 other. Further the complete atomization of the gasoline in connection with the kerosene makes it possible to introduce the kerosene at a lower velocity than would otherwise be practical. There is, therefore, a distinct advantage in combining the type of carburetor forming the primary and secondary elements of this carburetor.

What I claim as new is:—

1. In a carburetor, the combination of a 95 suction passage; a throttle valve in the passage; a fuel well; a fuel feeding means delivering fuel to the fuel well from a constant level; a spray device leading from below the fuel level in the fuel well to the 100 suction passage below the throttle and to above the fuel level; and an air delivery for the fuel well having an inlet more remote from the discharge end of the suction passage than the spray device and having a 105 capacity relatively to the spray device to maintain sub-atmospheric pressure in the fuel well responsive to and varying with the suction effort communicated through the spray passage for inducing a flow of fuel 110 varying as the suction effort for induction of air varies in the suction passage.

2. In a carburetor, the combination of a suction passage; a throttle valve in the passage; a restriction nearer the inlet than 115 the valve; a fuel well; a fuel feeding means delivering fuel to the fuel well from a constant level; means comprising an obstruction varying the flow of air through the restriction and spray devices leading from below the fuel level in the fuel well to the restriction in the suction passage below the throttle and to above the fuel level; and an air delivery for the fuel well having an inlet more remote from the discharge end 120 of the suction passage than the spray devices and having a capacity relatively to the spray devices to maintain sub-atmospheric pressure in the fuel well responsive to and varying with the suction effort communicated 125

- 6 cated through the spray passage for inducing a flow of fuel varying as the suction effort for induction of air varies in the suction passage.
- 5 3. In a carburetor, the combination of a suction passage; a throttle valve in the passage; a restriction nearer the inlet than the throttle valve; a fuel well; a fuel feeding means delivering fuel to the fuel well from 10 a constant level; a spray device leading from below the fuel level in the fuel well and terminating in nozzles extending into the restriction and to a point above the fuel level; and an air delivery for the fuel well 15 having an inlet more remote from the discharge end of the suction passage than the spray device and having a capacity relatively to the spray device to maintain sub-atmospheric pressure in the fuel well responsive to and varying with the suction effort communicated through the spray passage for inducing a flow of fuel varying as the suction effort for induction of air varies in the suction passage.
- 20 4. In a carburetor, the combination of a suction passage; a throttle valve in the passage; a restriction in the form of a Venturi tube in the passage nearer the inlet than the throttle valve; a fuel well; a fuel feeding means delivering fuel to the fuel well from a constant level; a spray device leading from below the fuel level in the fuel well to the suction passage and to above the fuel level; and an air delivery for the fuel well 25 having an inlet more remote from the discharge end of the suction passage than the spray device and having a capacity relatively to the spray device to maintain sub-atmospheric pressure in the fuel well responsive to and varying with the suction effort communicated through the spray passage for inducing a flow of fuel varying as the suction effort for induction of air varies in the suction passage.
- 30 5. In a carburetor, the combination of a suction passage; a throttle valve in the passage; a restriction nearer the inlet than the throttle valve; a fuel well; a fuel feeding means delivering fuel to the fuel well from a constant level; a spray device leading from below the fuel level in the fuel well to the suction passage and to above the fuel level; and an air delivery for the fuel well 35 having an inlet more remote from the discharge end of the suction passage than the spray device and having a capacity relatively to the spray device to maintain sub-atmospheric pressure in the fuel well responsive to and varying with the suction effort communicated through the spray passage for inducing a flow of fuel varying as the suction effort for induction of air varies in the suction passage.
- 40 6. In a carburetor, the combination of a suction passage; a throttle valve in the passage; a yielding valve in said passage nearer the inlet than the throttle valve; a fuel well; means for delivering fuel to said well from a constant level; a spray nozzle leading from the well to the restriction formed by the yielding valve; a restriction nearer the inlet to said passage than the yielding valve; and an air passage leading to the well from the suction passage at a point between the yielding valve and the last named restriction.
- 45 7. In a carburetor, the combination of a suction passage; a throttle valve in said passage; a yielding valve in said passage nearer the inlet than the throttle valve; a fuel well; means for delivering fuel to said well from a constant level; a spray nozzle leading from the well to the restriction formed by the yielding valve; a restriction nearer the inlet than the yielding valve, said yielding valve and restriction maintaining a substantially uniform velocity past the yielding valve; and an air passage leading to the well from the suction passage at a point between the yielding valve and the last named restriction.
- 50 8. In a carburetor, the combination of a suction passage; a throttle valve in the passage; a restriction nearer the inlet end of the passage than the throttle valve in the form of a Venturi tube; a fuel well; a fuel feeding means delivering fuel to the fuel well from a constant level; spray devices leading from below the fuel level in the fuel well and terminating in a nozzle extending from the wall of the Venturi tube into the 55 passage; and an air delivery for the fuel well having an inlet more remote from the discharge end of the suction passage than the spray devices and having a capacity relatively to the spray devices to maintain sub-atmospheric pressure in the fuel well responsive to and varying with the suction effort communicated through the spray passage for inducing a flow of fuel varying as the suction effort for induction of air varies in the suction passage.
- 60 9. The combination of a primary carburetor comprising a first suction passage, and means for delivering fuel to the first suction passage; and a secondary carburetor comprising a second suction passage, a fuel well; a spray nozzle leading from the fuel well to the second suction passage; and means for delivering air to the fuel well from the second suction passage at a point more remote from the discharge of the second suction passage than the point of delivery of the spray nozzle.
- 65 10. The combination of a primary carburetor comprising a first fuel receptacle, a first suction passage, and means for delivering fuel from the first fuel receptacle to the

- first suction passage; and a secondary carburetor comprising a second fuel receptacle, a second suction passage, a yielding valve opening only at a pre-determined suction in said second suction passage greater than a functioning suction on the primary carburetor, a fuel well, a spray nozzle leading from the fuel well to the restriction formed by the yielding valve, and means for delivering air to the fuel well.
11. The combination of a primary carburetor comprising a first fuel receptacle, a first suction passage, and means for delivering fuel from the first fuel receptacle to the first suction passage; and a secondary carburetor comprising a second fuel receptacle, a second suction passage, a yielding valve opening only at a pre-determined suction in said second suction passage greater than a functioning suction on the primary carburetor, a fuel well, a spray nozzle leading from the fuel well to the restriction formed by the yielding valve, a restriction in the second suction passage nearer the inlet than the yielding valve, and an air passage leading from the second suction passage to the feed well.
12. The combination of a primary carburetor comprising a first fuel receptacle, a first suction passage, and means for delivering fuel from the first fuel receptacle to the first suction passage; and a secondary carburetor comprising a second fuel receptacle, a second suction passage, a yielding valve opening only at a pre-determined suction in said second suction passage greater than a functioning suction on the primary carburetor, a fuel well, a spray nozzle leading from the fuel well to the restriction formed by the yielding valve, a restriction in the second suction passage nearer the inlet than the yielding valve, and an air passage leading to the well from the second suction passage at a point between the yielding valve and the restriction to the feed well.
13. In a carburetor, the combination of a main suction passage; a throttle valve in said passage; a primary carburetor discharging to said main suction passage comprising a fuel receptacle, a first suction passage, and means for delivering fuel from the fuel receptacle to the first suction passage; and a secondary carburetor discharging to the main suction passage, comprising a second fuel receptacle, a second suction passage, a yielding valve opening only at a pre-determined pressure in the main suction passage greater than a functioning suction on the primary carburetor, a fuel well, spray nozzles leading from the fuel well to the restriction formed by the yielding valve at a point at the side of said valve adjacent to the primary carburetor.
14. In a carburetor, the combination of a main suction passage; a throttle valve in said passage; a primary carburetor discharging to said main suction passage comprising a fuel receptacle, a first suction passage, and means for delivering fuel from the fuel receptacle to the first suction passage; and a secondary carburetor discharging to the main suction passage, comprising a second fuel receptacle, a second suction passage, a yielding valve opening only at a pre-determined pressure in the main suction passage greater than a functioning suction on the primary carburetor, and means for delivering fuel from the second fuel receptacle to the restriction formed by the yielding valve at a point at the side of said valve adjacent to the primary carburetor.
15. In a carburetor, the combination of a main suction passage; a throttle valve in said passage; a primary carburetor discharging to said main suction passage comprising a fuel receptacle, a first suction passage, and means for delivering fuel from the fuel receptacle to the first suction passage; and a secondary carburetor discharging to the main suction passage, comprising a second fuel receptacle, a second suction passage, a yielding valve opening only at a pre-determined pressure in the main suction passage greater than a functioning suction on the primary carburetor, a fuel well, spray nozzles leading from the fuel well to the restriction formed by the yielding valve at the side of said valve adjacent to the primary carburetor, a restriction in the second suction passage nearer the inlet to said passage than the yielding valve, and an air connection between the well and said second suction passage between the yielding valve and said restriction.
16. In a carburetor, the combination of a main suction passage; a throttle valve in said passage; a primary carburetor comprising a suction passage having a restriction in the form of a Venturi tube, a fuel well, nozzles leading from the fuel receptacle below the fuel level through the walls of the Venturi tube and into the air current passing through the Venturi tube, an air connection to the well leading from a point more remote from the throttle valve than the spray nozzles, a first fuel receptacle, and a connection between said first fuel receptacle and the well adapted to feed fuel by gravity and suction to said well; and a secondary carburetor comprising a second suction passage, a yielding valve opening said passage only on a pre-determined pressure in the main suction passage greater than a functioning suction on the primary carburetor, a second fuel well, spray nozzles leading

from said second fuel well to the restriction formed by the valve, a second fuel receptacle having a connection leading to said second well adapted to feed fuel to the well by gravity and suction, a restriction in the second suction passage nearer the inlet of said passage than said yielding valve, and an air connection leading from the second suction passage between the yielding valve and said last-named restriction.

17. In a carburetor, the combination of a suction passage having a closure shoulder thereon; a valve mounting adapted to form a closure with said shoulder and to form a

well between its walls and the walls of the 15 suction passage; a yielding valve carried by the valve mounting; a spray nozzle arranged in the valve mounting and leading from the well to the restriction formed by the yielding valve; a restriction for the suction passage carried by the valve mounting; and an air connection to the well having an inlet between the yielding valve and the restriction carried by the mounting.

In testimony whereof I have hereunto set 25 my hand.

FRANK H. BALL.
